Primary Examiner—Jeffrey Asch(74) *Attorney, Agent, or Firm*—Jones, Day, Reavis & Pogue(57) **CLAIM**

We claim the ornamental design for a die grinder, as shown and described.

DESCRIPTION

FIG. 1 is a perspective view of a die grinder embodying the ornamental design of the present invention;

FIG. 2 is a side view of the die grinder, the opposite side view being a mirror image;

FIG. 3 is a bottom view of the die grinder;

FIG. 4 is a top view of the die grinder;

FIG. 5 is a rear view of the die grinder; and,

FIG. 6 is a front view of the die grinder.

The broken line showings of FIGS. 1-6 are for illustrative purposes only and form no part of the claimed design.

1 Claim, 3 Drawing Sheets**OTHER PUBLICATIONS**

Copy of a 1-page single-sided undated Campbell Hausfeld catalog sheet labeled "Air Powered Cut-Off Tool" and "PL2535". No date given.

Copy of a 1-page single-sided undated Campbell Hausfeld catalog sheet labeled "Air Powered Cut-Off Tool" and "TL1035". No date given.

Copy of a 1-page single-sided undated Campbell Hausfeld catalog sheet labeled "Full Size Die Grinder" and "PL2521". No date given.

Copy of a 1-page single-sided undated Campbell Hausfeld catalog sheet labeled "Die Grinder" and "PL1520". No date given.

Copy of a 1-page single-sided undated Campbell Hausfeld catalog sheet labeled "Air Powered Die Grinder Kit" and "TL1023". No date given.
